FIG. 2

To all whom it may concern:

Be it known that I, Joseph A. Fossum, a citizen of the United States of America, residing at Minneapolis, Hennepin County, Minnesota, have invented a new, original, and ornamental Design for a Holder for Neckties or the like, of which the following is a specification, reference being had to the accompanying drawing, forming a part thereof.

Fig. 1 is a front elevation of a holder for neckties or the like, showing my new design,

Fig. 2 is an end elevational view thereof taken from the left of Fig. 1; Fig. 3 is a top plan view of the holder, and

Fig. 4 is a rear elevation of the same.

The dominant features of my design reside in the portions shown in full lines.

I claim:

The ornamental design for a holder for neckties or the like, substantially as shown and described.
